(57) **CLAIM**

We claim, the ornamental design for a buckle member for bags, as shown and described.

DESCRIPTION

FIG. 1 is a perspective view of a buckle member for bags, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a cross-sectional view taken along the lines 8-8 of FIG. 2;

FIG. 9 is a perspective view thereof with a female member of the buckle member;

FIG. 10 is an exploded perspective view of FIG. 1; and,

FIG. 11 is a bottom exploded perspective view of FIG. 1. The broken lines showing a female member of buckle member of bags in FIG. 9 are included in for the purpose of illustrating the invention in use and form no part of the claimed invention.
